ATTORNEYS.

A diaphragm member 18 is stretched across the entrance mouth of a closure shell 12 to extend over and along the outer surface of the bell-shaped portion 15 and there be secured by an elastic ring 19 stretched to such an extent as to tend to contract and bind the diaphragm 18 between it and the wall of the shell 12, it being located partly behind the bell-shaped portion 15 which serves to prevent the ring from being dislodged from its seated position. This ring also extends over the edge of the shell so as to protect the edge against bangs or marring should it be dropped, or more or less roughly contact with some other surface, thus this ring provides a resilient protecting edge for the cap, such as here illustrated, and also supports the diaphragm of the closure out of contact with a supporting surface when placed therein in the position shown in Figure 6.

The diaphragm 18 is of such resilient material that it will be readily stretched, and when the closure, such as shown in Figure 5 or Figure 6, is placed upon the neck 11 of the bottle it being merely necessary to force this cap downwardly over the neck of the bottle, causing the diaphragm 18 to stretch as it engages the edge of the bottle and to extend downwardly along the sides of the neck until the closure reaches such a point on the bottle that its tapered inner surface tightly grips some circumferential portion of the bottle, there being sufficient force exerted to cause some compression of the elastic seat, and thus a tight grip and a sealing of the mouth of the bottle. For removal, it is merely necessary to lift the cap from the neck of the bottle and the diaphragm which was under tension will contract to close the shell, such as illustrated in Figures 5 and 6; it is a very simple matter to clean or wash the portions of the cap with which the contents of the bottle may contact, if desired.

The closure is so formed that it may be set upright upon its end wall 14 so that the diaphragm 18 need not contact with any surface upon which the cap is set; or if the cap be laid upon its side or end, the rubber ring will support the diaphragm out of contact with the surface on which it rests.

It is also found that after the diaphragm has become stretched several times that it necessarily takes a concaved position slightly inwardly from the edge thereof, as at 25 in Figure 6, thus removing the portion which spans the opening of the bottle further from contact with this surface on which the closure is positioned to prevent it picking up any foreign matter which may be located thereon.

In order that this diaphragm may be freely moved into the shell and expanded therefrom, I have provided a vent opening 21 in the end wall 14 as well as a vent opening 22 in the lining 17 which may extend across this end wall, and in some instances I may desire to control this opening, as shown in Figure 7, by the valve 26 provided with a spring 27 for holding the same closed, and a finger piece 28 for controlling the action thereof.

In some cases I may provide a combined integral liner for the shell and diaphragm, as shown in Figure 8, thereby leaving a full metal surface to the edge of the cap. This liner comprises a side wall 30 of some suitable rubber composite and an integral diaphragm 31 of elastic rubber material. These portions 30 and 31 will usually be of a different composition but may be attached together by vulcanization making one homogeneous lining for the cap.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A bottle closure, comprising a body member, and a diaphragm member secured thereto and of a resilient material capable of being stretched across the open end of the bottle and along the outer surface thereof about the opening, and means in the body cooperating with the outer surface of the bottle to hold the diaphragm in closing position.
2. A bottle closure comprising a cup-shaped body member provided with a tapered compressible inner surface of a size to tightly fit the bottle neck at some point therealong, an elastic diaphragm positioned across the entrance opening to said body member and capable of being stretched across the open end of the bottle and along and between the outer surface of the bottle and said compressible inner surface.
3. A bottle closure comprising a cup-shaped body member provided with a tapered compressible inner surface of a size to tightly fit the bottle neck at some point therealong, an elastic diaphragm positioned across the entrance opening to said body member and capable of being stretched across the open end of the bottle and along and between the outer surface of the bottle and said compressible inner surface, and means to vent said body for the movement of said diaphragm thereinto.
4. A bottle closure comprising a cup-shaped body member having side and end walls with the inner surface of said side walls inclined sufficiently to provide a sticking taper and larger at the entrance end, and an elastic diaphragm member extending across to close the open end of said body member and stretchable to also extend along said side walls when forced to cause said tapered surface to move into engagement with the bottle.
5. A bottle closure comprising a cup-shaped body member having side and end walls with the inner surface of said side walls tapered and larger at the entrance end and provided with a compressible surface capable of tightly gripping the neck of the bottle when forced thereon, and an elastic diaphragm member extending across to close the open end of said body member.
6. A bottle closure comprising a cup-shaped body member having side and end walls with the inner surface of said side walls tapered and larger at the entrance end, an elastic diaphragm member extending across to close the open end of said body member, and an elastic ring under tension for securing said diaphragm in place against the surface of said side wall.
7. A bottle closure comprising a cup-shaped body member having side and end walls with the inner surface of said side walls inclined sufficiently to provide a sticking taper and larger at the entrance end and flaring into a bell shape and an elastic diaphragm member extending across said open end of said body member and over said bell-shaped end, and means on the outer surface of said body member to hold said diaphragm in place said diaphragm being stretchable to also extend along said side walls when forced to cause said tapered surface to move into engagement with the bottle.

8. A bottle closure comprising a cup-shaped body member having side and end walls with the inner surface of said side walls tapered and larger at the entrance end and flaring into a bell shape and an elastic diaphragm member extending across said open end of said body member and over said bell-shaped end, and an elastic ring on the outer surface of said body member to hold said diaphragm in place against the side wall thereof.

9. In combination, a bottle, a closure, comprising a body member extending across the top and along the sides of the bottle, and a diaphragm member secured thereto and of a resilient material capable of being stretched across the open end of the bottle and along the outer surface thereof and bound between the inside side walls of the closure and the outer surface of the bottle.
